INVENTOR

George F. Greene

UNITED STATES PATENT OFFICE.

GEORGE F. GREENE, OF PROVIDENCE, RHODE ISLAND.

DESIGN FOR A SCARF-PIN.

SPECIFICATION forming part of Design No. 23,758, dated November 6, 1894.

Application filed October 6, 1894. Serial No. 525,163. Term of patent $3\frac{1}{2}$ years.

To all whom it may concern:

Be it known that I, GEORGE F. GREENE, a citizen of the United States, residing at Providence, in the county of Providence, in the 5 State of Rhode Island, have invented and produced a new and original Design for Scarf-Pins, of which the following is a specification, reference being had to the accompanying drawing, forming a part thereof.

10 The head or ornamental portion of the scarf-pin has the outline, shape and appearance of a clown, in front view, dressed with a short conical hat, flaring - topped shoes, frilled knee-breeches and a jacket with ruffled sleeves, and apparently falling through

an egg - shell, the upper part of which is broken off leaving jagged edges. The legs appear to be thrust through openings in the egg - shell which is cracked and broken through. One arm is exposed bent outwardly 20 and downward beside the egg-shell. The figure is arranged upon the pin tongue at a slight angle therewith.

What I claim is—

15 The design for a scarf-pin herein shown and described.

GEORGE F. GREENE.
